ADDRESSING MACHINE

Roff Elliott, Watertown, Mass.

Application October 16, 1931. Serial No. 569,294

16 Claims. (Cl. 101—48)

This invention relates to printing and particularly to addressing machines wherein the addresses are carried by a series of stencils and are applied to a sheet by an inked printing roll 5 that is pressed against one face of the stencil to force ink through the address characters therein and onto a sheet held in contact with the opposite face of the stencil.

It is sometimes desirable to print something less than the entire address of the stencil. In compiling certain lists, for instance, only the name of the person whose name and address is carried by the stencil may be desired to be recorded. In another instance some other part 15 only of the total address may be desired.

Hence an object of the present invention is an addressing machine of the type above set forth arranged for the performance of such character of service.

20 A further object is the provision of an addressing machine wherein the printing roll is provided with a peripherally-recessed portion which is arranged to overlie and be out of contact with that portion of the stencil containing the unwanted address characters.

Another object is the provision of an addressing machine wherein the printing roll has a peripherally-located relieved or ink-free portion 30 that corresponds in width to the width of the unwanted section of the stencil, the roll being moved into such position that the relieved portion overlies the unwanted section of the stencil prior to and during each printing operation.

35 A further object is generally to improve the construction and operation of printing machines.

Fig. 1 is a side elevation, partly in section, of the essential elements of an addressing machine embodying the present invention.

40 Fig. 2 is a perspective detail of the printing roll and its rotating and holding mechanism, the roll being in printing engagement with a stencil.

Fig. 3 is a sectional elevation through the axis of the roll of Fig. 2.

45 Fig. 4 is a sectional detail taken along line 4—4 of Fig. 2.

The addressing machine here shown as embodying the present invention comprises a table 10 which supports a stencil track 12 along the length of which successive stencils 14 are moved in a step by step manner by any suitable mechanism not shown.

A platen 16 is located beneath the table 10 and is adapted to be raised by the cam face 18 of an upstanding arm 20 fixed to the shaft 22 and having an actuating arm 24, to press a sheet

adapted to receive the stencil characters against the bottom face of the stencil.

An ink roll 26 cooperates with the platen and is arranged to bear against the top face of the stencil to force the ink on the periphery of the roll through the address characters of the stencil onto the sheet. Said roll has a soft and yielding peripheral portion and is fixed to a shaft 28 that is journaled in opposed arms 30 carried by a frame 32 pivoted on a shaft 34 and reciprocated with the platen by means of the depending arm 36 of said frame, which arm is connected through a link 38 with the actuating arm 24.

The printing roll receives ink by a large transfer roll 40 which is in rolling engagement with the surface of the printing roll and is located between and is journaled in arms 42 that are pivoted to an upstanding bracket 44 so that the transfer roll can follow movements of the printing roll. The transfer roll receives ink from an ink roll 46 fixed to a shaft 48 journaled in the upper part of said bracket 44 and receiving ink from a supply roll 50. Said ink roll is rotated continuously by a belt 52 which passes about a pulley 54 on the shaft of the ink roll. The machine so far described is common in the art.

In accordance with the present invention means are provided whereby the printing of a portion only, as a single line, of all the address characters borne by the stencil. To this end the printing roll 26 is provided with a relieved peripheral portion or groove 56 that is long and wide enough to cover the unwanted address characters when the roll is in pressure contact with the stencil. In the arrangement shown the groove 56 is intended to overlie the last two lines, that is, the street, city and state characters, of the address, so that the ink-bearing portion of the roll comes in effective relation with only the first 90 line, containing the name characters, of the address. Hence ink will be forced through only the name characters and only those will be printed.

Mechanism is also provided which assures the positioning of the printing roll in proper relation with the unwanted characters of the stencil at each printing operation. To this end, the printing roll is rotated continuously, except when it is held from rotation during the printing operation, by an extensible belt 58 which is passed about a pulley 60 fixed to the shaft 28 of the printing roll and also about a pulley 62 fixed to the continuously rotated shaft 48 of the ink roll 46. The belt is adapted to slip in its engagement with one of said rolls, however, when the printing roll is 105 held against rotation.

The rotation of the printing roll is governed by a pin or projection 64 which outstands from the shaft 28 of the printing roll adjacent one of the arms 30 of the roll supporting frame. A latch or plunger 63 is movable axially in said arm under urge of a spring 63. When the printing roll is elevated above the stencil, the plunger is disposed by said spring away from the path of movement of said pin 64 so that the printing roll is free to 10 rotate. The position of the plunger is controlled by a bracket 70 which is fixed to one of the rails of the stencil track 12 and upstands between the plunger-carrying arm 30 and an end of the printing roll. When the printing roll is in elevated 15 and inactive position the inner end of the plunger 63 is disposed above the top of the bracket. When, however, the arms 30 are lowered toward a stencil the plunger engages a cam face 72 at the upper end of the bracket and is moved outwardly there- 20 by to dispose its outer end in the path of movement of the pin 64 carried by the printing roll shaft, thereby to hold said shaft from rotation. The plunger is held by the cam face of the bracket against retractile movement while the printing 25 roll is in engagement with the stencil. The relation between the pin, plunger and groove of the printing roll is such that the roll is held against rotation with its groove 56 above the unwanted characters of the stencil when the printing roll 30 is in active position.

It is apparent that the groove or relieved portion 56 will have different dimensions, in different rolls, depending upon the area occupied by the unwanted characters of the stencil.

35 The transfer roll 40 is arranged to make but light pressure engagement with the periphery of the printing roll, the engaging pressure being controlled by the adjustable screw 74 which is threaded in a supporting arm of the transfer roll 40 and bears against the frame 32 of the printing roll.

I claim:

1. A stencil printing machine comprising a 45 rotatable printing roll having a portion of its periphery that is adapted to receive ink and another portion that is free from ink, and means to stationarily position the roll with its ink-free peripheral portion in opposed relation with unwanted printing characters of a stencil during the 50 printing operation.

2. A stencil printing machine comprising a rotatable ink-carrying printing roll having a recess in its periphery, and means to stationarily 55 position said roll with its recess in opposed relation with unwanted printing characters of a stencil at the time an ink-carrying portion of the roll is in engagement with other characters of the stencil during the printing operation.

60 3. A stencil printing machine comprising a rotatable printing roll having an ink-receiving peripheral portion and an ink-free peripheral portion, means to rotate said roll and apply ink to the ink-receiving portion thereof, and means to hold the roll stationary with the ink-free portion of said roll in opposed relation with unwanted printing characters of a stencil at the 65 time of the printing operation.

4. A stencil printing machine comprising a 70 printing roll that is normally free to rotate and has an ink-bearing and also an ink-free peripheral portion, and means which holds said roll against rotation and with its ink-free portion in predetermined relation with a stencil during the printing operation.

75 5. A stencil printing machine comprising a

printing roll that is normally free to rotate and has an ink-receiving surface provided with a groove therein, and means which holds said roll against rotation with said groove aligned with selected printing characters of a stencil during 80 the printing operation.

6. A stencil printing machine comprising a 85 rotatable printing roll having ink-receiving and ink-free peripheral portions, means for rotating said roll, and means effective prior to the engagement of the roll with a stencil to arrest the rotation of said roll with the ink-free portion thereof aligned with selected printing characters of a stencil.

7. A stencil printing machine comprising a 90 rotatable printing roll having ink-receiving and ink-free peripheral portions, means for reciprocating said roll into and out of printing engagement with a stencil, and means effective during the movement of said roll toward the stencil for holding the roll stationary with the ink-free portion of said roll in alignment with selected 95 printing characters of the stencil.

8. A stencil printing machine comprising a 100 rotatable printing roll having ink-receiving and ink-free peripheral portions, means for reciprocating said roll into and out of printing engagement with a stencil, means for rotating said roll, and means effective during the movement of said 105 roll toward the stencil for arresting the rotation of said roll with the ink-free portion thereof aligned with selected printing characters of the stencil.

9. A stencil printing machine comprising a 110 rotatable printing roll having ink-receiving and ink-free peripheral portions, means for rotating said roll constantly, which means is adapted to slip when the roll is held stationary, and means for engaging said roll prior to the engagement of the roll with a stencil for holding the roll 115 stationary with the ink-free portion thereof aligned with selected characters of the stencil.

10. A stencil printing machine comprising a 120 rotatable printing roll having ink-receiving and ink-free peripheral portions, means for reciprocating said roll into and out of engagement with a stencil, means for rotating said roll constantly, which means is adapted to slip when the roll is held stationary, and means responsive to the 125 movement of said roll toward the stencil for engaging said roll and holding it against rotation with the ink-free portion aligned with selected characters of a stencil.

11. A stencil printing machine comprising a 130 rotatable printing roll having an ink-receiving portion and an ink-free portion that is less in extent than the extent of printing characters of the stencil, and means automatically effective prior to the engagement of said roll with the 135 stencil for holding said roll stationary with the ink-free portion aligned with certain only and the ink-receiving portion aligned with other printing characters of the stencil.

12. A stencil printing machine comprising a 140 stencil holder, a rotatable printing roll disposed above said holder having ink-receiving and ink-free peripheral portions, a supporting frame in which said roll is rotatable and which is reciprocable to move said roll into and out of engagement with a stencil in said holder, and means carried by said frame and engageable with said roll during movement of said frame toward said holder for holding said roll against rotation and with the ink-free portion thereof in a prede- 145 termined position.

13. A stencil printing machine comprising a stencil holder, a rotatable printing roll disposed above said holder having ink-receiving and ink-free peripheral portions, a supporting frame in which said roll is rotatable and which is reciprocable to move said roll into and out of engagement with a stencil in said holder, and means including a stationary element engaged by a part of said frame during movement thereof toward said holder for holding said roll against rotation and with the ink-free portion thereof in a predetermined position. 80
14. A stencil printing machine comprising a stencil holder, a frame reciprocable toward and away from said holder, a printing roll having ink-receiving and ink-free peripheral portions and a shaft journalled in said frame, an ink transfer roll in constant engagement with the periphery of said printing roll, a stationarily-supported continuously-rotated ink roll for applying ink to said transfer roll, a belt connecting said ink and printing rolls for rotating said printing roll, said belt adapted to slip when said printing roll is held stationary, said shaft having a projection, a latch carried by said frame for engaging said projection and holding said roll stationary with said ink free portion in a predetermined location, and means rendered effective by movements of said frame for operating said latch. 85
15. A stencil printing machine comprising a stencil holder, a frame reciprocable toward and away from said holder, a printing roll having ink-receiving and ink-free peripheral portions and a shaft journalled in said frame, means for constantly rotating said roll, said shaft having a projection, a latch carried by said frame for engaging said projection and holding said roll stationary with said ink free portion in a predetermined location, and means rendered effective by movements of said frame for operating said latch. 90
16. A stencil printing machine comprising a stencil holder, a frame reciprocable toward and away from said holder, a printing roll having ink-receiving and ink-free portions and a shaft journalled in said frame, an ink transfer roll in constant engagement with the periphery of said printing roll, a stationarily-supported continuously-rotated ink roll for applying ink to said transfer roll, a belt connecting said ink and printing rolls for rotating said printing roll, said belt adapted to slip when said printing roll is held stationary, said shaft having a projection, a latch carried by said frame for engaging said projection and holding said printing roll stationary with its ink-free portion in a predetermined position, and stationary means engaged and released by said latch during movements of said frame toward and away from said holder for operating said latch to engage and release said projection. 95
